US00D998661S

(12) **United States Design Patent** (10) **Patent No.:** **US D998,661 S**
Makino et al. (45) **Date of Patent:** **** Sep. 12, 2023**

(54) **WIRE ELECTRIC DISCHARGE MACHINE**

(71) Applicant: **FANUC CORPORATION**, Yamanashi (JP)

(72) Inventors: **Yoshinori Makino**, Yamanashi (JP); **Akiyoshi Kawahara**, Yamanashi (JP); **Hisanori Kouda**, Yamanashi (JP)

(73) Assignee: **FANUC CORPORATION**, Yamanashi (JP)

(**) Term: **15 Years**

(21) Appl. No.: **29/755,410**

(22) Filed: **Oct. 20, 2020**

(30) **Foreign Application Priority Data**

Apr. 20, 2020 (JP) 2020-008057

(57) **CLAIM**

The ornamental design for a wire electric discharge machine, as shown and described.

DESCRIPTION

FIG. 1 is a first perspective view of a wire electric discharge machine showing our new design;

FIG. 2 is a second perspective view thereof;

FIG. 3 is a front view thereof;

FIG. 4 is a rear view thereof;

FIG. 5 is a right side view thereof;

FIG. 6 is a left side view thereof;

FIG. 7 is a top plan thereof; and,

FIG. 8 is a bottom plan view thereof.

The broken lines depict portions of the wire electric discharge machine that form no part of the claimed design.

1 Claim, 8 Drawing Sheets
